[57] CLAIM

The ornamental design for an incontinence pad, as shown and described.

DESCRIPTION

FIG. 1 is a side and end perspective view of an incontinence pad, seen from above, showing our new design;

FIG. 2 is a side and end perspective view thereof, seen from the opposite side of FIG. 1;

FIG. 3 is a top plan view thereof;

FIG. 4 is a right side elevational view thereof; the opposite side thereof is identical thereto;

FIG. 5 is a bottom plan view thereof;

FIG. 6 is an end elevational view thereof;

FIG. 7 is an end elevational view thereof, opposite that shown in FIG. 6;

FIG. 8 is top perspective view of a second embodiment thereof;

FIG. 9 is a top plan view thereof;

FIG. 10 is a right side elevational view thereof; the opposite side thereof is identical thereto;

FIG. 11 is a bottom plan thereof; and

FIG. 12 is an end elevational view thereof; and,

FIG. 13 is an end elevational view thereof, opposite that shown in FIG. 12.
